FLOOR SLAB

Herbert H. Bunker, Jersey City, N. J.

Application March 19, 1931. Serial No. 523,740

16 Claims. (Cl. 72—78)

This invention relates to floor slabs and has for a principal object the production of a floor slab comprising steel and filling material such as concrete and in which the steel is so arranged as to provide a rigid and strong slab capable of 5 withstanding the effects of concentrated loads wherever applied. Floor slabs are supported similarly to beams; that is, at their ends and sometimes intermediate their ends but they are unlike beams in that they are relatively wide in 10 comparison with their depths. The result is that a concentrated load like the wheel of a vehicle applied at a point between supports causes flexure in all directions from the point of application of the load and an accompanying tendency 15 to cause "dishing" of the slab. A constantly recurring error in slab design is attributable to the endeavors of engineers to produce a slab of minimum weight without giving sufficient consideration 20 to the fact that the large surface area character of a slab requires strength enough in all directions to prevent excessive dishing. Dishing of a slab results in the rupture of the bond between the steel and the filling material and 25 also affects the life of the slab. Slabs have been produced which are strong enough to resist excessive flexure in one direction, as from support to support, but which are not sufficiently strong to prevent flexure across the slab as 30 would cause disintegration of the filling material. Accordingly, it is an object of the present invention to provide a slab in which the steel construction is such as to adequately brace the slabs in all directions and prevent such flexing and dishing 35 of the slab as would break the bond or crush filling material and to accomplish this in a slab of minimum weight for a given load.

In addition to providing a slab in which the steel is so arranged as to adequately care for 40 forces of tension and compression on its end and upper portions, it is a further object of the invention to provide such a slab as this which is capable of withstanding negative bending movements so as to be useful as a continuous beam 45 over several supports. To these ends the floor slab of the present invention is provided with a steel plate which serves as the lower surface thereof and which has bars associated therewith. The bars are arranged in two sets, one set 50 consisting of a grating and the other set comprising members joining the grating with the steel plate, substantially throughout the area of the slab. The members intermediate the grating and plate are so placed as to contribute 55 strength to the structure where strength is de-

sired and are not used solely for the purpose of joining the floor grating to the plate. By welding the intermediate members at the places they come into contact with the plate and floor grating a unitary reinforced steel structure is obtained. Since I prefer the use of bent bars for 60 intermediate members, I have chosen to accompany the disclosure of my invention with illustrations of structures showing different arrangements of such bars. Any of these structures 65 produces a thin and relatively light slab capable of withstanding the ordinary load and wear to withstand which much heavier road structure is generally used.

Other objects involving novel constructions and 70 combinations of parts will appear in the specification and in the claims thereof, setting forth a preferred embodiment of my invention which may be fully understood from the detailed description and drawings, in which:

Fig. 1 is a plan of a floor slab in which parts 75 are broken away to show the relation of the bars.

Fig. 2 is a section on line 2—2 of Fig. 1.

Fig. 3 is a view of the adjoining ends of the 80 slabs illustrated in Fig. 1, with parts broken away to show the manner of joining.

Fig. 4 is a section on line 4—4 of Fig. 1.

Fig. 5 is a plan of another form of floor slab 85 with parts broken away to show the relation of the bars.

Fig. 6 is a section on line 6—6 of Fig. 5.

Fig. 7 is a section on line 7—7 of Fig. 5.

Fig. 8 is a plan of a portion of another form 90 of floor slab.

Fig. 9 is a section on line 9—9 of Fig. 8.

Fig. 10 is a plan of still another form of floor slab with parts broken away to show construction.

Fig. 11 is a section on line 11—11 of Fig. 10.

Fig. 12 is a plan of a detail showing one mode 95 of joining the floor slabs.

Fig. 13 is a section on line 13—13 of Fig. 12.

Ordinary gratings of bent bars have been used for providing the tensile support required on the under surface of a slab but such gratings have 100 been found to be stronger in one direction than in the other for resisting tensile forces. They are relatively weak for resisting tensile forces in a direction lateral to the longitudinal extension of the bent members or bars. Floor slabs 105 having ordinary gratings at their under surfaces are, therefore, subject to dishing as also are such floor slabs which consist of bars such as rails or angle-irons placed side-by-side and supported by means extending crosswise. When such floor 110

slabs are subjected to concentrated loads the lower longitudinal members are likely to spread from one another and cause destruction of the bond of filling material and its loss. Of course,

5 floor slabs of the character just referred to may be made in such a manner as to not possess the disadvantage stated to a detrimental degree, but such a floor slab would be of a weight greatly in excess of the slab of the present invention.

10 In Figs. 1, 2, 3 and 4 I have illustrated one embodiment of my invention in which the steel plate 10 forms the bottom of the slab. It is expected that each slab be of such an area as will be suitable for any particular job but, ordinarily, for a bridge, individual slabs will be connected together to form the flooring. Slabs for a road or floor surface of a bridge are laid adjacent to each other and are bolted or otherwise fastened together with proper allowance for 15 expansion. As illustrated in Fig. 1, a single floor slab may extend from one beam 11, across a second beam 12 to another beam 13.

As may be readily seen in Figs. 1, 2 and 3, a flange is provided all around the floor slab but 20 within the area of the plate 10. This flange 14 extends upwardly for the total depth of the slab and forms a box edge. The flange may consist of a strip of metal welded or otherwise secured to the steel plate or it may take the form of one leg of an angle-iron suitably secured to the plate.

30 A standard form of grating may be used for the upper portion of a floor slab, but I prefer to use a grating of a kind illustrated herein. One form of this grating consists of a plurality of bent bars 15, Figs. 1 and 2, which are welded or otherwise secured to each other in a manner well-known. This upper grating, consisting of bars 15, is joined to the box flange 14 at such 35 places as at 16, 17, which are points of contact between the floor grating and the flange.

40 Before the floor grating 15 is positioned the inside steel construction of a floor slab must be completed. This construction preferably consists of bars running lengthwise of the floor slab and joining the floor grating. Bent bars such as 18, are preferable. They are not necessarily joined to each other but they are welded to the plate 10 and the floor grating 15 and thereby serve to unify the steel structure of the entire slab. It 45 will be noted that these bars 18, as illustrated in Figs. 1, 2 and 4, stand on edge and have their edges contacting with the plate 10.

50 It is apparent that by joining all of the bars 18 to the plate 10 and the grating 15 a steel skeleton is produced in which the steel is well distributed throughout the slab. In fact, the dimensions of the grating bars, intermediate bars and plate may be so proportioned as to locate 55 the neutral axis practically on the center line of a slab, thus providing balance in section with maximum strength for any allowable weight per slab. While each of such bars may run the length of a slab I prefer to use several discontinuous bars in prolongation of each other, as 60 illustrated. This arrangement reduces the weight of a slab without sacrificing its strength. The skeleton construction is sufficiently strong to support all loads which the slab may be called 65 upon to carry and in fact it is possible to carry on bridge building operations, including the travel of vehicles thereover for the transportation of concrete, before any concrete or other filling material has been poured. Because of 70 the uninterrupted character of a plate a most

efficient tension member is present where the greatest tensile forces act, and this fact, coupled with the presence of steel throughout the slab, creates a strong and rigid slab.

80 In general floor slabs should be held down because of vibration to which they are subject. For this purpose they may be welded or bolted to beams or, as shown in Figs. 3 and 4, each of the slabs may be clamped to a beam at its ends by means of clamps 21 and bolts 22. These clamps engage the flanges of the I-beam upon which the end of a slab rests.

85 After the slabs have been laid in place all of the open area within the box flange 14 is filled with concrete or other filling material. This material serves as a road surface and may extend above the upper edges or just to the edges of the floor grating 15 and the upper edge of the box flange 14. The space 23 between the box flanges of adjacent floor slabs may be filled with mastic or with material capable of permitting expansion 90 between the various floor slabs.

95 In Figs. 5, 6 and 7 I have illustrated another form of floor slab in which the plate 26 and the floor grating 27 is similar to that of the floor slab just described. However, the box flange 28, extends around the outer edge of the plate 26. The steel intermediate the plate 26 and floor grating 27 consists of bent bars 29 which run longitudinally from one end to the other end of the slab. 100 These bars are placed with their edges in vertical planes and rotated 90° from the position of the intermediate bars shown in Fig. 1. These bars 29 are likewise welded to the plate 26 and the floor grating and produce a structure which 105 is uniformly distributed with steel throughout. This floor slab is also to be filled with some filling material 30. The separation of the filling material into channels is avoided. As may be readily seen from Figs. 6 and 7, the concrete below 110 and above the intermediate bars 29 is directly associated with the concrete between the intermediate bars 29.

115 The construction of the floor slab illustrated in Figs. 8 and 9 is of the same order as that of Fig. 5 except that the floor grating 31 is of a different design. This floor grating has straight members 32 between pairs of bent bars 33.

120 Another manner in which I provide steel throughout the thickness of my floor slab is illustrated in Figs. 10 and 11. In a floor slab of this construction the slab is made similar to that illustrated in Fig. 5 except that the intermediate bent members 35 run across the slab. This construction likewise has the advantage that avenues or 125 long channels in the filling are obviated. By the proper placing of the steel and the elimination of avenues in the filling material the probability of failure of the concrete because of shear is 130 eliminated.

135 Another advantage of the construction of the present invention is that the lower plate serves as a mould for receiving the filling material when it is being poured. The filling material may readily distribute itself throughout the area of the slab and produce an integral mass of concrete. It has been found that the present floor slab may be relied on for resisting torsional strains which commonly occur between stringers and beams on a bridge. Therefore in the design of the bridge the ordinary cross bracing which is used to counteract the effect of torsional and weaving strains may be designed with a view of utilizing the floor slabs for assisting in cross-bracing. It is readily understood that the main body or steel con- 140

struction of the floor slab may be completed in the shop and later laid according to specifications and filled with concrete or other filling material for surfacing the slab. When an individual slab 5 wears or if a defect should develop, such a slab may be easily removed without disturbing a large area of road way.

It is apparent that different provisions may be made for joining the floor slabs to each other and 10 for holding them in place next to each other. In Figs. 12 and 13 I have illustrated a tie-joint in which a plate 37 is bolted to the flanges 38 and 39 of adjacent slabs. This plate also has portions 40, 41 extending below the upper flange of 15 an I-beam 42 in such a manner as to engage the same.

I do not wish to be limited to the shapes of the various bars which may be used for it is apparent that many other forms of gratings are satisfactory for serving as the upper portion of my floor slab and that the bars intermediate the floor grating and plate may take many and varied forms. It is, however, my intention to 20 produce a skeleton steel structure in which the steel is distributed throughout the thickness of 25 the slab to such an extent as is necessary to counteract the longitudinal shear and diagonal shear ordinarily occurring within the interior of a slab or beam. The vertical shear existing at any 30 point because of a concentrated load is carried by the steel of the slab, and the impact caused by a travelling load as it progresses across different bars of the grating is transmitted to the steel plate through the intermediate bars which lie 35 just beneath the upper grating. The concrete or other filling material is not called upon to withstand tension or to buttress heavy impact blows to which the grating is subjected when in use.

40 What I claim is:

1. As an article of manufacture, a floor slab frame comprising a series of bent bars joined together with the edges forming opposite sides of a grating, a plate forming the bottom of the 45 frame, said plate being spaced from all members of said grating, a flange extending from said plate and enclosing the outer edge of said grating, bars intermediate the grating and plate, said intermediate bars extending in the same 50 direction as the bent bars of the grating and having a width equal to the spacing between the grating and the plate, and welded joints between the intermediate bars and the grating and plate.

2. As an article of manufacture, a floor slab 55 frame comprising a series of bent bars joined together with the edges forming opposite sides of a grating, a plate forming the bottom of the frame, said plate being spaced from all members of said grating, a flange extending from 60 said plate and enclosing the outer edge of said grating, bars intermediate the grating and plate, each of said bars being joined to both the under side of the grating and the plate at several places along their lengths, the intermediate bars and 65 the bent bars of said grating being associated in such a manner as to provide steel reinforcing throughout the slab without dividing the volume within the box flange into disconnected spaces.

3. As an article of manufacture, a floor slab 70 frame comprising a series of bent bars joined together with the edges forming opposite sides of a grating, a plate forming the bottom of the frame, said plate being spaced from all members of said grating, a flange extending from said 75 plate and enclosing the outer edge of said grat-

ing, and bars intermediate the grating and plate and joined to each, said last named bars being distributed throughout substantially the entire area between the grating and the plate.

4. As an article of manufacture, a floor slab 80 frame comprising a series of bent bars joined together with the edges forming opposite sides of a grating, a plate forming the bottom of the frame, a box flange extending upwardly from said plate, said box flange being joined to said grating, and bars intermediate the grating and plate and joined to each, said last named bars being distributed throughout substantially the entire area between the grating and the plate. 85

5. The combination set forth in claim 4 in 90 which the bars intermediate the grating and plate are on edge with one edge of each welded to the grating and the other edge welded to the plate.

6. As an article of manufacture, a floor slab 95 frame comprising a grating having longitudinal bars joined together, said grating forming the upper structure of the frame, a plate spaced from said grating and forming the lower structure of the frame, and means separating the 100 grating and plate and maintaining them in fixed relation to each other, said means comprising bars fastened to the under surface of said grating and to the plate.

7. The combination set forth in claim 6 in 105 which the bars intermediate the grating and plate run lengthwise of the frame and are spaced at intervals across the frame.

8. The combination set forth in claim 6 in 110 which the bars intermediate the grating and the plate run crosswise of the frame and are spaced at intervals from end to end of the frame.

9. As an article of manufacture, a floor slab 115 comprising a steel grating having bars with edges up and interstices between bars, a plate, a flange upstanding from said plate and spaced from the edge of said plate, bent bars arranged between said grating and plate and welded to each, and filling material within the box formed by 120 said plate and upstanding flange, said filling material being unitary and extending into the interstices of said bent bars and grating.

10. As an article of manufacture, a floor slab 125 frame comprising a steel plate for its lower surface, a grating in its upper portion, a flange bordering the grating and extending to the upper surface of the grating from the steel plate, and bars intermediate the grating and the steel plate, said bars running lengthwise of the frame and being welded to both the grating and the plate. 130

11. As an article of manufacture, a floor slab frame comprising a lower plate, longitudinally extending bent bars having bends transverse to the bars, said bars resting upon and connected to said plate at the lower bends of said bars, and 135 an upper grating spaced from said plate and connected to the upper bends of the aforesaid bent bars.

12. As an article of manufacture, a floor slab 140 frame comprising a lower plate, longitudinally extending bent bars having bends transverse to the bars, said bars resting upon and connected to said plate at the lower bends of said bars, and an upper grating spaced from said plate and connected to the upper bends of the aforesaid bent 145 bars, said upper grating comprising members which extend longitudinally and in the same general direction as that in which the bent bars extend.

13. As an article of manufacture, a floor slab 150

frame comprising a lower plate, an upper grating section spaced therefrom and intermediate structure between said upper grating and said lower plate, said intermediate structure comprising a plurality of spaced bent bars having their lower bends connected to the plate and their upper bends connected to the upper grating.

14. As an article of manufacture, a floor slab frame comprising a single metallic plate of substantial width and of a length approximately twice its width, a plurality of individual bent bars attached to the upper surface of said plate, said bars being independent of each other and spaced over substantially the entire area of the plate, and an upper grating section substantially coextensive with said plate, said grating section being attached to the bent bars which extend from the grating section to the plate and unite the same in a composite frame.

20

15. As an article of manufacture, a floor slab frame comprising a lower plate, an upper grating structure and intermediate structure comprising individual bars running widthwise of the plate and spaced from one another lengthwise of the plate, said bars having bends transverse to the bars with lower bends welded to the surface of the plate and upper bends welded to the grating structure.

80

16. As an article of manufacture, a floor slab frame comprising a lower plate, an upper grating structure substantially coextensive with the lower plate and spaced therefrom, and intermediate structure comprising individual bars distributed throughout the area of said plate and standing on edge upon the surface of said plate, said bars having their lower edges welded to the plate and their upper edges welded to the grating structure.
